UNITED STATES PATENT OFFICE.

ROBERT A. FORESMAN, OF ESSINGTON, PENNSYLVANIA, ASSIGNOR TO WESTINGHOUSE ELECTRIC & MANUFACTURING COMPANY, A CORPORATION OF PENNSYLVANIA.

MECHANICAL STOKER.

Application filed June 22, 1920. Serial No. 390,855.

To all whom it may concern:

Be it known that I, ROBERT A. FORESMAN, a citizen of the United States, and a resident of Essington, in the county of Delaware and State of Pennsylvania, have invented a new and useful Improvement in Mechanical Stokers, of which the following is a specification.

This invention relates to mechanical 10 stokers, and more particularly to stokers of the underfeed type in which the fuel is supplied to an inclined overfeed grate at a point near the front and the refuse therefrom discharged at a point near the rear of 15 the grate.

The object of my invention is the production of a simple and comparatively inexpensive stoker construction which operates efficiently and economically and which 20 employs a minimum number of moving elements, thereby reducing the power required for its operation and the cost of maintenance.

In furnaces of the usual overfeed type the 25 grate bars extend across the furnace in parallel relation and from the front coal receiving end of the furnace to the rear ash discharging end thereof, and are inclined from the front to the rear of the furnace. The 30 bars are usually reciprocated by an engine disposed at the front of the furnace for the purpose of gradually shaking down and agitating the fuel so that fuel supplied to the grate near the upper end thereof is caused 35 to gravitate toward the bottom of the grate from whence the refuse is discharged into a pit adjacent the lower end of the grate.

Grate bars of this type must necessarily 40 be made of heavy material in order to withstand the load imposed thereon and the high temperatures to which they are exposed, and consequently considerable energy is absorbed in moving the heavy bars loaded with fuel over the bearings which, on account of the 45 excessive heat, are impracticable to lubricate. The wear of the bars and bearings is consequently excessive, and as a result thereof, such parts must be frequently renewed.

It is an object of this invention to pro-

duce a stoker wherein the fuel is supplied 50 to the grate uniformly throughout the width of the furnace and distributed and advanced to the ash pit in such manner that efficient combustion is maintained.

A further object of the invention is to 55 produce a furnace having the above characteristics of performance which may be actuated with a minimum of power and has a minimum number of moving elements compared with stokers of the same capacity and 60 having moving grate bars.

Another object is to produce a stoker 65 wherein the grate bars or tuyères are stationary and are arranged in transverse rows across the entire width of the furnace, and wherein the fuel is agitated and advanced by means of pivoted sectors adapted to be operated in recesses between the grate bars.

These and other objects which will be 70 made apparent throughout the further description of the invention are attained in the stoker embodying the features illustrated in the accompanying drawings wherein:

Fig. 1 is a longitudinal section through a 75 furnace stoker embodying features of my invention, and Fig. 2 is a plan view of the stoker illustrated in Fig. 1.

Referring to the drawings, the furnace includes a front wall 5, a rear wall 6, and side walls 7 forming a rectangular space in which 80 the stoking mechanism is located. The fuel supporting grate includes, as shown, three separate transverse sections 8, 9, and 10 disposed one beneath the other in different parallel planes in such manner as to provide recesses 11 and 12 between the adjacent sections. Each grate section comprises three separate groups of rectangular tuyère blocks 13 mounted upon stepped tuyère supporting frames 14 which in turn are supported upon 85 the main grate supporting frame disposed beneath the grate sections in a manner to be hereinafter described. The tuyères of each section are crowned by locking tuyères 16 which, in the case of the top section 8, are 90 secured to the rear wall 17 of the fuel retort 18 by means of bolts 19. The locking tuyères 16 of the center section 9 and the rear section 95

10 are secured respectively to castings 20 and 21 which form bottom closures for the recesses 11 and 12 respectively.

The casting 20 is supported upon transverse angle irons 22 which extend across the furnace and are secured at intervals to vertical beams 22' which in turn are supported upon the frame disposed beneath the grate sections. The casting 21 is supported upon 10 a transverse I-beam 23 which forms a part of the said frame.

Fuel is supplied to the grate sections by means of a pair of rams 24 mounted beneath the discharge openings 25 of the supply hoppers 26 and adapted to be reciprocated forward and rearward by means of suitable engines or motors 27. Each ram is rectangular in shape and operates in a guide slot 28 formed beneath the hopper 26, and is adapted 20 to force fuel passing through the discharge openings 25 through the inlet 29 of the retort 18 in a well known manner. However, the retorts employed in the present embodiment of the invention are provided with 25 discharge openings of such width that, when placed side by side, they serve to provide a fuel retort extending entirely across the front of the furnace from which coal is uniformly discharged on to the grate sections 30 along their entire width.

As the plungers 24 continue to force fuel into the retort, the fuel gravitates over the uppermost grate section 8 and falls into the recess 11. Beneath the lowermost tuyère 13 of the upper section 8, an agitator sector or fuel moving member 30 is pivoted at 31 to a support 32 carried by the casting 20. This agitator or fuel moving member is provided with a series of tuyère blocks 33 through 40 which air from the air box 34 located beneath the grate sections may pass, and the lower end of the agitator is provided with a shoe 35 adapted to move over the concave surface 36 of the casting 20 in close proximity thereto so as to provide a close sliding joint through which the fuel cannot readily pass.

The agitator 30 is adapted to be oscillated so as to swing upward and rearward out of 50 the recess 11 into the position similar to that in which the lower agitator 37 in the recess 12 is shown. The agitator 37 is in every particular identical to the agitator 30 and will not therefore be described in detail.

55 Fuel falling into the recess 11 from the grate section 8 is forced upward and rearward by the rearward swing of the agitator 30, and is moved on to the central grate section 9 from whence it falls into the recess 12 60 and into contact with the swinging agitator 37 which, in turn, moves it rearwardly on to the final or lowermost grate section 10, from whence it is discharged on to the dump grate 38. The grate may be of any suitable construction such as that illustrated.

The agitators 30 and 37 are adapted to be oscillated by the reciprocatory movement of the plunger and are connected thereto by operating mechanism which includes a lever 39 pivotally mounted for oscillation upon a 70 bracket 40 secured to the transverse retort supporting channel frame 41. The upper end of this lever is slidably connected at 42 to the ram 24 while the lower end is slidably connected at 43 to a connecting rod 44 which extends rearwardly and which is supported at its forward end in a bracket 45 secured to the frame 41 and at its rearward end in a bracket 46 carried by the beam 22'. The agitators 30 and 37 are each provided with a 80 forwardly extending lug 47 to which ends of the links 48 and 49 respectively are pivotally connected. The other ends of the said links are pivotally connected to oscillating levers 50 and 51 respectively. The lever 50 is pivoted at a point 52 intermediate its ends to a bracket 53 carried by the angle irons 22, and its lower end is pivotally connected to the connecting rod 44 by means of a slot and pin connection 54.

The lower end of the lever 51 is pivotally connected at 56 to a bracket 57 secured to the I-beam 23 and is pivotally connected to the rear end of the connecting rod 44 by means of a link 58. It will be seen from the foregoing that rearward movement of the connecting rod 44 will cause the agitator 30 to swing forwardly into the recess and away from the fuel bed, while at the same time the agitator 37 is caused to swing rearwardly out of the recess to the fuel bed. The agitators, therefore, operate at all times in opposite directions, and while the uppermost agitator is forcing fuel onto the central grate section, the lowermost agitator 105 is moving into the recess to receive fuel forced off the grate section. The cooperation of the agitators just described insures a uniform distribution of the fuel throughout the width of the furnace and a gradual 110 progressive movement of the fuel toward the dump grate 38.

Because of the effective agitation of the fuel intermediate the ends of the grate surface, the thickness of the fuel bed is maintained practically constant during the operation of the stoker. Therefore, the danger of forming blow holes through which excessive quantities of air may flow is eliminated. The tuyère 14 and locking tuyère 16 are provided with air passages through which air from the air box beneath the grates may flow to the fuel bed.

In the construction illustrated it will be seen that the grate sections 8, 9, and 10 extend from one side wall 7 to the other and are made in three transversely aligned portions. Two retorts 18 having their combined discharge opening extending substantially across the width of the furnace and 120

served by two fuel hoppers 26 and two rams 24 supply fuel uniformly across the width of the furnace, and the uniform distribution of the fuel is maintained by the agitators 5 throughout the length and width of the grate surface.

The fuel agitators are the only moving parts in contact with the fuel upon the grates, and because of their pivoted bearings offer less resistance to movement than rams and grates having sliding engagement with unlubricated surfaces. The construction is simple, and the under structure is such that it may readily be fabricated from 10 commercial steel shapes, thereby eliminating the use of heavy castings which are objectionable because they frequently warp due to temperature variations.

While I have described and illustrated but 20 one embodiment of my invention, it will be apparent to those skilled in the art that various changes, modifications, substitutions, additions and omissions may be made in the apparatus illustrated without departing 25 from the spirit and scope of the invention as set forth by the appended claims.

What I claim is:—

1. In furnace stoker, a longitudinal overfeed grate unit having a plurality of fixed 30 inclined sections spaced to provide a recess between adjacent sections, means for supplying fuel to the overfeed grate, and a fuel moving member pivotally mounted in said recess between adjacent sections and adapted 35 to be oscillated toward the front and rear of the furnace.

2. In a furnace stoker, a longitudinal overfeed grate unit having a plurality of fixed inclined sections spaced to provide a recess 40 between adjacent sections, means for supplying fuel to the overfeed grate, and a fuel moving member suspended within said recess between adjacent sections upon a pivot having its axis disposed transversely of the furnace, said fuel moving member adapted 45 to swing rearwardly and forwardly whereby fuel in contact therewith is agitated and moved toward the rear of the furnace.

3. In a furnace stoker, the combination of 50 a longitudinal inclined grate unit, having a plurality of fixed inclined sections spaced to provide a recess between adjacent sections, of a fuel moving member pivotally mounted in said recess between adjacent 55 sections for oscillatory movement toward and from the rear of the furnace adapted to receive fuel from one section and move it onto an adjacent section toward the rear of the furnace.

60 4. In a furnace stoker, the combination with an inclined grate having a declined stepped series of fixed inclined sections spaced to provide recesses between adjacent sections and adapted to receive fuel at its 65 uppermost section and discharge refuse at

its lowermost section, of fuel moving members, pivotally mounted in the recesses between adjacent sections for oscillatory movement toward and from the discharge end of the grate and each adapted to receive fuel 70 from an upper section and move it toward the discharge end of a lower section.

5. In a furnace stoker, a longitudinal overfeed grate unit having a stepped series of 75 fixed inclined sections spaced to provide a recess between adjacent sections, reciprocating means for supplying fuel to the overfeed grate, a fuel moving member pivotally mounted in said recess between two adjacent sections and adapted to be oscillated toward and from the discharge end of the grate, and means connecting the said fuel moving member with the said reciprocating means whereby the said member is oscillated 80 by movement of the reciprocating means.

6. In a furnace stoker, an inclined overfeed grate having a plurality of fixed inclined sections spaced to provide recesses between adjacent sections, reciprocating means 85 for supplying fuel to the overfeed grate, a plurality of fuel moving members pivotally mounted in the recesses between adjacent sections extending transversely of the furnace and adapted to be oscillated toward and from the discharge end of the grate, and driving means for oscillating the members in one recess forwardly and in an adjacent recess rearwardly by a single movement of the reciprocating means.

7. In a furnace stoker, an inclined overfeed grate having a plurality of fixed inclined sections spaced to provide recesses between adjacent sections, means for supplying fuel to the overfeed grate, a plurality 90 of fuel moving members pivotally mounted in the recesses between adjacent sections extending transversely of the furnace and adapted to be oscillated toward and from the discharge end of the grate, and driving means connecting the said members for swinging the members in any recess in one direction while the members in an adjacent recess are swung in the opposite direction.

8. In a furnace stoker, a longitudinal inclined overfeed grate unit having at least 100 two fixed sections and provided with a recess extending transversely between adjacent sections, a fuel moving member pivoted beneath the portion of the grate section which forms the upper boundary of the recess and adapted to oscillate so that the lower end of the member may swing forwardly into the recess and thereby permit fuel to fall from the portion of the grate section above the recess into the said recess, and may swing upwardly and toward the discharge or rear end of the grate and out of the recess, thereby moving fuel discharged from the section above the recess to the section below the recess, and a closure means 105 110 115 120 125 130

for the bottom of the recess adapted to prevent the escape of fuel from between the bottom of the said member and the portion of the grate which forms the lower boundary 5 of the said recess.

9. In a furnace stoker, a longitudinal inclined overfeed grate unit having at least two fixed inclined sections extending substantially across the furnace and provided 10 with a transversely disposed recess between adjacent sections extending substantially the entire width of the said grate, means for feeding fuel to one section from a point above the said recess, and a fuel moving 15 member extending substantially the entire length of the recess pivotally mounted within the recess so that the lower end of the said member may be swung out of the said recess for the purpose of moving the fuel 20 toward the discharge end of the grate.

10. In a furnace stoker, a plurality of inclined grate sections arranged in an inclined series in different substantially parallel planes and spaced apart so as to provide 25 recesses between adjacent sections, and fuel moving members pivotally mounted within the recesses adapted to be swung rearwardly for moving fuel entering the recesses onto the grate sections beneath.

- 30 11. In a furnace stoker, an underfeed retort section extending transversely at the front of the stoker substantially the width of the furnace, an overfeed grate at the rear thereof having a stepped series of fixed inclined sections, said sections being spaced apart to provide recesses between adjacent sections, reciprocating means for underfeeding fuel into said retort in a sheet or layer of substantially the width of the furnace, 35 and thence to the overfeed section throughout its width, and fuel moving members pivotally mounted within the recesses adapted to be swung rearwardly for moving fuel entering the recesses onto the grate sections 40 beneath.

45 12. In a furnace stoker, an underfeed retort section extending transversely at the front of the stoker substantially the width of the furnace, an overfeed grate at the rear thereof having a stepped series of fixed inclined sections, said sections being spaced apart to provide recesses therebetween extending substantially the entire width of the furnace, reciprocating means for underfeeding fuel into said retort in a sheet or layer of substantially the width of the furnace, and thence to the overfeed grate throughout its width, fuel moving members extending 50 substantially the length of and pivotally mounted within the recesses and adapted to be swung in and out of the recesses for the purpose of moving fuel toward the discharge end of the grate, and means connecting the said fuel moving members with the said reciprocating means whereby the said member is oscillated by movement of the reciprocating means.

55 ing fuel into said retort in a sheet or layer of substantially the width of the furnace, and thence to the overfeed section throughout its width, and fuel moving members extending substantially the length of and pivotally mounted within the recesses and 60 adapted to be swung in and out of the recesses for the purpose of moving fuel toward the discharge end of the grate.

65 13. In a furnace stoker, an underfeed retort section extending transversely at the front of the stoker substantially the width of the furnace, an overfeed grate at the rear thereof having a stepped series of fixed inclined sections spaced to provide a recess between adjacent sections, reciprocating means for underfeeding fuel into said retort in a sheet or layer of substantially the width of the furnace, and thence to the overfeed section throughout its width, fuel moving members pivotally mounted in the recess formed between adjacent sections and adapted to be oscillated toward and from the discharge end of the grate, and means connecting the said fuel moving members with the said reciprocating means whereby the said members are oscillated by movement of the reciprocating means.

70 14. In a furnace stoker, an underfeed retort section extending transversely at the front of the stoker substantially the width of the furnace, an overfeed grate at the rear thereof and having a stepped series of fixed inclined sections, said sections being spaced apart to provide recesses therebetween extending substantially the entire width of the furnace, reciprocating means for underfeeding fuel into said retort in a sheet or layer of substantially the width of the furnace, and thence to the overfeed grate throughout its width, fuel moving members extending 75 substantially the length of and pivotally mounted within the recesses and adapted to be swung in and out of the recesses for the purpose of moving fuel toward the discharge end of the grate, and means connecting the said fuel moving members with the said reciprocating means whereby the said member is oscillated by movement of the reciprocating means.

80 15. In testimony whereof, I have hereunto 85 subscribed my name this 17th day of June, 1920.

ROBERT A. FORESMAN.
